UNITED STATES PATENT OFFICE

164,978

PORTABLE COOKING STOVE

Dewey H. Bitney, Albion, Mich., assignor to Union
Steel Products Company, Albion, Mich.

Application August 28, 1950, Serial No. 11,969

Term of patent 14 years

(Cl. D81—10)

To all whom it may concern:

Be it known that I, Dewey H. Bitney, a citizen of the United States, residing at Albion, county of Calhoun, State of Michigan, have invented a new, original, and ornamental Design for a Portable Cooking Stove, of which the following is a specification, reference being had to the accompanying drawing, forming a part hereof:

Fig. 1 is a front perspective view of a portable cooking stove, showing my new design.

Fig. 2 is a rear elevational view on a slightly smaller scale.

Fig. 3 is a top plan view.

The side not shown is a duplicate of the side shown in Fig. 1.

I claim:

The ornamental design for a portable cooking stove, as shown and described.

DEWEY H. BITNEY.
